TELEGRAPH SYSTEM.

1,324,130.

Specification of Letters Patent.

Patented Dec. 9, 1919.

Application filed May 28, 1918. Serial No. 237,045.

To all whom it may concern:

Be it known that we, LOUIS A. MORTIMER and GEORGE C. CUMMINGS, a citizen of the United States and a subject of the King of Great Britain, respectively, residing at New York, in the county of New York, State of New York, and at East Orange, in the county of Essex, State of New Jersey, respectively, have invented certain new and useful Improvements in Telegraph Systems, of which the following is a full, clear, concise, and exact description.

This invention relates to telegraph systems and more particularly to systems for the simultaneous transmission of a plurality of messages over one and the same line circuit.

The object of this invention is a circuit arrangement whereby an additional alternating current telegraph channel may be superimposed on a composite telephone line without introducing mutual interference between the several channels of communication.

It is common practice in the telephone art to operate a direct current Morse telegraph channel over each wire of a telephone pair. Each of these telegraph channels may furthermore be duplexed so that simultaneously with the use of a pair of wires for telephone purposes, four telegraph messages may be sent, two from each end of the line. Such an arrangement requires special equipment for signaling the telephone stations inasmuch as the usual 16 cycle ringing current would otherwise cause false signals in the Morse instruments. Consequently, the usual low frequency ringing current is made to control the application of higher frequency ringing current (usually about 135 cycles) to the line, which in turn at the receiving end of the line operates a relay to connect the 16 cycle current to the local signaling apparatus.

In applying an additional alternating current telegraph channel to such a system a current frequency and a circuit arrangement must be chosen which will cause the least likelihood of disturbance with or disturbance from the other channels of communication.

This invention therefore provides a pair of transformers, one of which has a winding in series with the main line conductor

and the other of which has a winding in series with the artificial line branch of the duplex network. Bridged between the mid-points of these windings is a receiving circuit for the alternating current telegraph signals which contains inductance and capacity so chosen in value as to make the receiving circuit roughly resonant to the frequency of the alternating current telegraph signals. The receiving circuit is linked inductively with the receiving apparatus proper which consists of a series of amplifiers and filtering circuits leading to the signal indicating device, the filtering circuits being chosen to admit the passage of the alternating current telegraphic frequencies (preferably about 60 cycles) and to exclude other frequencies such as the composite ringing frequency, the telephonic frequencies and the lower frequency "Morse thumps" from the direct current duplex.

Each of the transformers above mentioned is equipped with a transmitting winding, the two being connected in series with an alternating current source and a transmitting key. Each of the two transformers is furthermore provided with a third winding connected one with the other to form a closed circuit linking the main line with the artificial line and serving to lessen danger of interference between the direct current duplex and the alternating current telegraph channel.

In the drawing, Figure 1, there is shown an equipment suitable for the transmission and reception of telegraphic impulses by means of direct currents and also equipment for the transmission and reception of telegraphic signals by means of alternating currents, while in Fig. 2 there are shown in plan form two metallic telephone circuits arranged in a manner suitable for carrying out the service features of this invention.

In describing this system it will first be pointed out that the equipment shown in Fig. 1 may be understood as typical of four telegraphic equipments indicated by the reference characters 1, 2, 3 and 4 in Fig. 2 of the drawing, these equipments being arranged to operate from earth over respective line conductors 5, 6, 7 and 8 which form a first and a second telephone line circuit respectively indicated by the reference char-

acters A and B. As shown in the drawing, a first telephonic equipment provides for operation over the conductors 5 and 6 of the circuit A, a second telephonic equipment 6 may be provided for operating over the conductors 7 and 8 of the circuit B, while a third telephonic equipment may be employed to operate in superposed or so-called phantom relation over the two physical 10 circuits A and B. By means of this arrangement it results that during the time the several telephone equipments are in use the several direct current telegraphic channels and the several alternating current telegraphic 15 channels may also be in operation.

In more specifically describing this system, attention will now be directed to Fig. 1 of the drawing. In considering the direct current portion of the telegraphic equipment 20 a transmitting means 10 may be operated to selectively control associated sources of grounded line current indicated by the conventional plus and minus signs at this transmitter. Such currents after traversing the 25 windings of an impedance coil 11 reach the apex or neutral point of a duplex equipment formed by ratio arms 12 and 13. The currents divide at this point over a first path which may be traced through the differentially connected windings 16 and 17 30 of a transformer 15, thence through a conductor 20 and an impedance coil 21 (Fig. 2) to, say, the line conductor 5 of the circuit "A". The second path extends through 35 the bridge arm 13, the differentially connected windings 26 and 27 of a transformer 25, thence through the windings of an impedance unit 39 and the capacity and resistance paths of an artificial line 30 to earth. 40 As well understood in connection with duplex circuits, such outgoing currents transmitted by the key 10, although neutralized and non-effective with respect to a receiving relay 31, may traverse the lead 20 and 45 the line conductor 5 to actuate a receiving relay in a similar duplex equipment at a distant station. In a converse manner, direct current impulses originating at a distant station may arrive over the line conductor 5 50 (Fig. 2), pass through the impedance coil 21, thence by way of the lead 20, the windings 17 and 16 of the transformer 15 (Fig. 1), to actuate the receiving relay 31, the armature of which controls contacts in the 55 circuit of a receiving equipment not shown.

For transmitting telegraphic signals by means of alternating currents, a transmitting key 40, when depressed, closes contacts 41 to connect a source 42 of alternating current, preferably of sine-wave form, through 60 the windings 18 and 28 of the transformers 15 and 25 respectively to ground. In addition to closing the contacts 41 such operation of the key 40 separates contacts 43, thereby opening a normally closed loop cir-

cuit which includes the windings 19 and 29 of the transformers 15 and 25 respectively. The purpose of this loop circuit will presently appear. Alternating currents in the transformer windings 18 and 28 cause corresponding current changes in the windings 17 and 27 of the transformers 15 and 25 respectively. One terminal of the winding 17 is connected through a condenser 32 and the winding 36 of a transformer 35 to earth, 70 while the other terminal of the winding 17 is connected by the lead 20 and the inductance coil 21 (Fig. 2) to the line conductor 5 at the distant end of which is a suitable receiving equipment presently to be described. 75

At the transformer 25 currents induced from the winding 28 are manifested in the winding 27 which is connected to permit such induced currents to circulate in a closed loop formed through a first grounded condenser 33, a second condenser 34 and a winding 37 of the transformer 35 to earth. Since the line portion of the transmitted alternating currents which traverse the winding 36 of the transformer 35 are counteracted by the artificial line portion of the alternating currents which traverse the winding 37 of this transformer, neutralization is established in the transformer 35 and a receiving system connected to the winding 38 of 95 this transformer is therefore not affected by such transmitted alternating currents.

In the reception of messages transmitted from a distant station alternating currents may arrive over the line conductor 5 (Fig. 2), pass through the impedance coil 21, the conductor 20, winding 17 (Fig. 1) of the transformer 15, thence by way of the condenser 32 and winding 36 of the transformer 35 to earth. Such incoming currents through the winding 36 set up corresponding currents in the winding 38 of the transformer 35 and since the latter winding is connected to form a closed loop through a current amplifier magnet 45 such current changes will in turn establish like current effects in a microphone pile 46 which may be similar to a transmitter button.

Variations of current potential from a source 47, as set up by the microphone 46, 115 act through a transformer 48 to operate a second amplifier which comprises operating coil 49 and microphone pile 50. In turn the microphone 50 causes current changes from a source 51 which may, through a transformer 52, become effective in a network or filter system comprising transformers 53 and 54 and respectively associated condensers 55 and 56. A polarized relay 57 connected to the secondary windings of the transformer 120 54 is arranged to normally connect battery through the winding of a relay 58 and an impedance unit 59 to earth. For convenience, the armature of the polar relay 57 may be biased by means of a retractile spring as 130

shown to normally retain the circuit just traced through the relay 58. The relay 58 being normally energized, connects an associated source of positively poled current through the winding of a polar relay 60 to earth. This current normally biases relay 60 to open contacts in a local battery circuit including a device 61 which may be a sounder or other suitable receiving means.

- 10 Incoming impulses of alternating currents from the line as traced cause the armature of the relay 57 to be reciprocated in step with the reversals of these currents and such alternate disconnecting of the circuit traced 15 through the relay 58 permits the armature of this relay to release and connect a source of negatively poled current through the polar relay 60 in substitution of the positive current already described. Although each 20 positive half-wave or impulse through the relay 57 may bias the armature of this relay to close the circuit through the relay 58, the operating time constant of the relay 58 with respect to the frequency of the received 25 alternating currents is such that this relay is practically deenergized during the presence of incoming alternating currents, thereby maintaining negative bias of the relay 60 in retaining the device 61 operated.
- 30 From this description of the manner in which incoming alternating currents are received, it will be clear that relatively feeble currents from the line circuit will receive a first and second amplification, following 35 which they will pass through the filtering network to arrive in the form of currents which more nearly resemble the form of the alternating currents impressed on the line conductor at the distant station, thereby 40 insuring reliable and proper operation of the receiving devices to be controlled.

The windings 19 and 29 on the transformers 15 and 25 are used for the purpose of compensating for unbalance in the direct 45 current duplex system. The circuit through these windings is normally closed by the back contact 43 of the key 40 and forms an inductive coupling between the line side and the artificial line side of the duplex network. If, for example, there is a momentary unbalance causing more current to pass 50 from the transmitting key 10 to line 20 than to the artificial line 30, there will be a transfer of current from the winding 19 to the winding 29 to compensate for this unbalance. The alternating current receiving system is therefore less liable to disturbance 55 from such unbalance than if the inductive coupling were not used.

60 The condensers 66 and 67 are bridged around the ratio arms 12 and 13 to absorb any inductive kicks caused by the operation of the transmitting key 10, while a third condenser 68 is bridged across the terminals 65 of the relay 31 to provide a path for the

alternating current signals and to prevent such signals from interfering with the operation of the said relay.

Referring to Fig. 2 of the drawing, a path for telephonic currents over the first 70 circuit A may be traced from the line conductor 5 through condenser 70, the windings 72 of a transformer 71, a condenser 74, thence returning to the distant station over the second line conductor 6 of this circuit. 75 Such currents in the winding 72 of the transformer 71 set up corresponding currents in the winding 73 to act over a circuit one side of which is formed through the contacts 81 of a relay 80, a conductor 85, 80 the contacts 86 of a relay 90 to the "tip" contact member 92 of a telephone jack 91; the other side of the circuit consists of the contacts 82 of the relay 80, a conductor 95, the contacts 87 of the relay 90 to a "ring" 85 contact member 93 of the jack 91. As well understood in the art, telephonic devices (not shown) may be included with the jack 91 for communicating by way of the paths already traced over the circuit A. In order 90 that call-signals may be operated over the line circuit in connection with the telephonic traffic without such call-signals interfering with either the direct current or the alternating current telegraphic service, the devices shown intermediate the transformer winding 73 and the telephone jack 91 are provided and will now be described.

In initiating a telephone call-signal by way of the jack 91 of the circuit A, it will 100 be understood that equipment, not shown, but included with this jack is provided for applying an alternating current of relatively low-frequency, as, say, approximately 16 cycles per second to the contact members 92 and 93. Such connection with the jack 91 separates its normal contacts to disconnect a signal receiving device 94 which, for convenience, is shown in the form of a "drop". The low frequency alternating 105 current may traverse the contacts 86 of the relay 90, the conductor 85, a condenser 100, the windings of a polarized relay 101 to the conductor 95, thence returning over the contacts 87 of the relay 90 to the opposite side 110 of the connection at the jack 91. The armature of the relay 101 is so arranged that its contacts 102 and 103 are normally open. Under the action of alternating currents 115 through this relay its armature will be reciprocated in phase therewith to alternately close the contacts 102 and 103. When the contacts 102 close, a source of grounded battery 104 will be connected through these contacts and associated resistances with a bus 120 conductor 105. From this bus conductor the circuit divides over one path formed through an alternating current relay 106 and a battery 107 to earth and over another path which includes the winding of a second al- 125 130

ternating current relay 108 and a battery 109 to earth. While the battery 104 is connected to act in differential relation with respect to the batteries 107 and 109, the potential of the battery 104 is greater than the potential of the batteries 107 and 109. Ordinarily, a relation in which the potential of the battery 104 is twice the potential of either of the other batteries, has been found to give satisfactory results. During the time the contacts 102 are closed it will therefore be clear that current may flow from the battery 104 over the circuits traced through each of the alternating current relays 106 and 108, and conversely current in an opposite direction will flow from the batteries 107 and 108 through the respective alternating current relays to earth during instants the contacts 103 of the relay 101 may be closed. In this manner it will be clear that alternating current effects may be active through the relays 106 and 108 during the time alternating currents may be applied by way of the jack 91, as described, and it will further be clear that the frequency of the alternating currents through these relays will be in phase with the alternating currents applied at the jack. The relay 106 is of such design or adjustment that it will not be affected by the low frequency alternating currents, the relay 108, however, is so proportioned or adjusted as to readily respond to the low frequency currents described. Operation of the relay 108 completes a circuit from a source of current 109 through the winding of a relay 110 to earth. Operation of the relay 110 completes a circuit from an associated battery which extends through the windings of a relay 111 and the relay 80 to earth. Relay 111 thereby operated completes a loop circuit which includes an alternating current generator 112 and a winding 114 of a transformer 113. Operation of the relay 80 causes separation of its contacts 81 and 82 to disconnect the conductors 85 and 95, and in closing its contacts 83 and 84 this relay connects a secondary winding 115 of the transformer 113 in a closed loop circuit which includes the winding 73 of the transformer 71. The frequency of the current produced by the generator 112 is relatively high, say, approximately 133 cycles per second, and such currents may traverse the line conductors 5 and 6 of the metallic circuit A to reach a distant station and there operate a telephone call signal which may be typical of the signal 94 shown at the present station.

In describing operations whereby a telephone call-signal originating at a distant station may be received at the present station, let it be assumed that at the distant point operations are carried out in a manner similar to that just described in connection with the sending out of high frequency sig-

naling currents from the present equipment. Such incoming alternating currents act through the transformer 71 to complete circuit over the contacts 81 and 82 of the relay 80, thence by way of the conductors 85 and 95 through the condenser 100 and relay 101. The relay 101 is so constructed or adjusted that it may readily respond to alternating currents of either low or high frequency, therefore, in responding to the high frequency currents the contacts 102 and 103 of this relay are alternately closed in phase therewith to establish alternating current effects of a corresponding frequency over the operating circuits already traced through the relays 106 and 108. In this case, the low frequency relay 108 will continue inert while the high frequency relay 106 will close its contacts to complete a circuit from a battery 116 to operate a relay 117. The operation of the latter relay connects a battery 116 to operate the relay 90 and separation of the contacts 86 and 87 of the latter relay disconnects the conductors 85 and 95 from the jack 91, while closure of the contacts 88 and 89 of this relay connects a low frequency generator 118 to act over the normal contacts of the jack 91 in operating the drop signal 94, it being understood, of course, that no connection would be present in the jack 91 during times it may be necessary to receive a call signal, as described, from a distant station.

The various telephonic equipments, direct current telegraphic equipments, and alternating current telegraphic equipments are so arranged and proportioned, one equipment with another, that the various call-signal control and telephonic operations described may be carried on without interfering one-signaling method with another even when a telephone equipment, similar to that shown and described in connection with the circuit A, is included with the transformer 71 for carrying out telephonic service in connection with the physical circuit B, while similar equipment may be connected to the conductors 96 and 97 for telephone service over the phantom circuit formed jointly over the circuits A and B as shown.

The condensers 75 and 78 and impedance coils 76 and 77 serve to absorb or prevent other than telephonic currents reaching the telephonic equipment just described, a ground connection established intermediate the coils 76 and 77 being provided as a drainage circuit to play a part in this arrangement for preventing interference between telegraphic and telephonic currents. Condensers 79 connected to earth from points respectively intermediate the impedance coils 21 and the associated telegraphic equipments serve further to prevent extraneous or surge currents which may be set up by the telegraphic instruments from reach-

ing the telephone portion of the equipments and also to prevent loss of telephonic currents through the telegraphic devices.

In the working of the phantom telephone circuit already mentioned, telephonic and call-signal current paths may be traced by way of the conductor 96 to a neutral or simplex point on the coil 72 of the transformer 71, from which point the currents may differ 5 equally in differential relation over the conductors 5 and 6 of the circuit A and after passing through similar equipment at a distant station these currents may return in similar equal differential relation over the line conductors 7 and 8 of the circuit B to a central point on the winding 72 of the transformer 71 of the latter circuit, thence by way of the conductor 97 to the opposite side of the telephone equipment of the phantom circuit. In a converse manner incoming telephonic currents from a distant station may act through the phantom circuits just traced and be manifested on telephonic device assumed as connected to the conductors 96 and 97.

In addition to its being understood that similar telephonic equipment may be present at a distant station for each one of the three telephone channels described, it will also be understood that telegraphic equipments corresponding with the equipments 1, 2, 3 and 4 may also be present at a distant station or stations.

In further increasing the service capacity of the physical circuits A and B telegraphic equipments of the direct current and alternating current types as already described may be connected to operate in earth return relation over the leads 96 and 97 as multiplexed over the two physical circuits, respectively.

Although the arrangement chosen for illustrating this invention is considered to represent a preferred embodiment thereof, it will be understood that changes in the arrangement of the equipment may be made without departing from the spirit of this invention.

What is claimed is:

1. The combination with a line conductor and a direct current duplex telegraph system connected thereto having an artificial line, two ratio arms and a receiving circuit bridging said ratio arms and connecting said line conductor with said artificial line, of a receiving circuit for alternating current signals bridged between said line conductor and said artificial line, and a compensating coupling between said line conductor and said artificial line.

2. A system for signaling by alternating currents comprising a real line, an artificial line, a transformer having a winding in series with said real line, a second transformer having a winding in series with said

artificial line, a receiving circuit connecting the mid-points of said windings, transmitting windings on said transformers, and a source of alternating current and a transmitting key in circuit with said transmitting windings.

3. A system for signaling by alternating currents comprising a real line, an artificial line, a transformer having a winding in series with said real line, a second transformer having a winding in series with said artificial line, a circuit connecting the mid-points of said windings, and an inductive coupling between said real line and said artificial line.

4. The combination with a line conductor and a duplex telegraph system connected thereto and having two ratio arms and an artificial line for balancing the real line, of a transformer having a winding in series with said line conductor, a second transformer having a winding in series with said artificial line, a bridge circuit connecting the mid-points of said windings, and a receiving device inductively connected to said bridge circuit.

5. A system for signaling by alternating currents comprising a line conductor, an artificial line, a transformer having a winding in series with said line conductor, a second transformer having a winding in series with said artificial line, a receiving circuit connecting the mid-points of said windings, transmitting windings on each of said transformers, a normally closed circuit including a third winding on each of said transformers, a source of alternating current, and means for simultaneously supplying current from said source to said transmitting windings and for opening said normally closed circuit.

6. A signaling system comprising a real line, an artificial line, a transformer having a winding in series with said real line, a second transformer having a winding in series with said artificial line, a circuit containing inductance and capacity connecting the mid-points of said windings, and a signaling indicating device inductively connected to said circuit.

7. The combination with a direct current duplex telegraph system comprising a line conductor and an artificial line, means for signaling by alternating currents over said line conductor, simultaneously with the operation of said direct current system, comprising a transformer having a winding in series with said line conductor, a second transformer having a winding in series with said artificial line, a bridge circuit containing a direct current receiving relay connecting a terminal of one of said windings with a corresponding terminal of the other of said windings, a second bridge circuit containing inductance and capacity connect-

125

130

- ing the mid-points of said windings and an alternating current signal-receiving device inductively connected to said second bridge circuit.
5. 8. The combination with a direct current duplex telegraph system comprising a line conductor and an artificial line, of means for signaling by alternating currents over said line conductor simultaneously with the 10 operation of said direct current system comprising a transformer having a winding in series with said line conductor, a second transformer having a winding in series with said artificial line, an alternating current 15 receiving circuit connecting the mid-points of said windings, a transmitting winding on each of said transformers, and a source of alternating current and a transmitting key in circuit with said transmitting wind- 20 ings.
9. The combination with a telephone line conductor and a bridge duplex telegraph equipment connected thereto and comprising two ratio arms and an artificial line, 25 of a direct current signal receiving circuit and an alternating current signal receiving circuit both bridged between said line conductor and said artificial line, and an inductive coupling between said line conductor 30 and said artificial line.
10. The combination with a telephone line
- conductor of auxiliary means for signaling over said conductor by alternating currents comprising a transformer having a winding in series with said line conductor, an 35 artificial line, a second transformer having a winding in series with said artificial line, a circuit bridged between the mid-points of said transformers and resonant at the frequency of said auxiliary signals, a signal 40 receiving device and a selective circuit connecting said receiving device with said receiving circuit and arranged to exclude telephonic frequencies from said receiving device. 45
11. In combination with a line conductor, an artificial line, a circuit containing capacity connecting said line circuit with said artificial line, a transformer having a winding in series with said line circuit, a second 50 transformer having a winding in series with said artificial line, a bridge circuit containing capacity and inductance connecting the mid-points of said windings, a signal indicating device and a selective connecting circuit between said bridge circuit and said device and signal amplifying means in said connecting circuit. 55

In witness whereof, we hereunto subscribe our names this 23rd day of May A. D., 1918. 60

LOUIS A. MORTIMER,
GEORGE C. CUMMINGS.
